F. CLARK.
COMBINATION KEY BARREL CONSTRUCTION.
APPLICATION FILED OCT. 10, 1919. RENEWED DEC. 4, 1920.

1,369,727.

Patented Feb. 22, 1921.

FIG. 4.

UNITED STATES PATENT OFFICE.

FRANCISCO CLARK, OF DURANGO CITY, MEXICO.

COMBINATION-KEY-BARREL CONSTRUCTION.

1,369,727.

Specification of Letters Patent. Patented Feb. 22, 1921.

Application filed October 10, 1919, Serial No. 329,815. Renewed December 4, 1920. Serial No. 428,376.

To all whom it may concern:

Be it known that I, FRANCISCO CLARK, a citizen of Mexico, and resident of Durango City, Durango, Mexico, have invented a new and Improved Combination- Key- Barrel Construction, of which the following is a full, clear, and exact description.

This invention relates to a combination key of the type having longitudinally adjustable ward members.

One of the objects of this invention is to provide a new and improved combination key so arranged and constructed that a plurality of adjustable ward members may be provided in a minimum space, so that the ward members may be conveniently and readily adjusted to various combinations, corresponding to the setting of tumbler members of a lock.

20 A further object of this invention is to provide a combination key of simple and compact construction having means so arranged and constructed that ward members may be conveniently and readily adjusted longitudinally of the key body, without the necessity for the use of movable stops and spring members.

A further object of this invention is to provide a combination key having adjustable ward members therein, so constructed and arranged that when the key is inserted within the key hole of a lock, the ward members will actuate and position certain tumbler members of the lock, while another portion of the key, preferably the key body, engages a bolt actuating element of the lock mechanism, so that relative rotary motion may be effected between the wards and the key body or other part of the key engaging 40 the bolt actuating element of the lock.

Still another object of this invention is to provide a combination key of simple and compact construction, which is inexpensive to manufacture, and having the parts thereof so constructed and arranged that the same may be readily assembled, adjusted or replaced.

With these and other objects in view, the invention consists in the construction and arrangement described in the following description, illustrated in the accompanying drawings, and more particularly pointed out in the appended claims.

In the practical embodiment shown, the 55 above objects are accomplished by providing

a key comprising a key body including a cylindrical core having a handle portion connected therewith, and a plurality of ward members arranged about the core, a means being provided to permit adjustment of the wards longitudinally of the core, the construction and arrangement being such as will permit relative rotary movement between the wards and the key body. The combination key may be used for any suitable lock.

In the accompanying drawings and description, similar characters of reference designate corresponding parts in the several views.

Figure 1 is a longitudinal sectional view on the line 1—1 of Fig. 2, showing the key positioned in the key hole of a combination lock.

Fig. 2 is a transverse sectional view on the line 2—2 of Fig. 1.

Fig. 3 is a broken sectional view on the line 3—3 of Fig. 1, showing the arrangement of the tumblers of the lock corresponding to that of the key.

Fig. 4 is an enlarged perspective view of one of the wards.

Fig. 5 is an elevational view showing the cylindrical core portion and handle of the key.

Fig. 6 is an end elevational view of Fig. 5 showing more clearly one form of the projecting end portion for engaging the bolt actuating element of the lock.

With reference to the drawings, representing a practical embodiment of the invention, the key is shown as comprising a handle 1 which may be of any suitable form, and a core portion 2 preferably cylindrical, forming part of the key body. Connected to the core, and extending from one end thereof, is a projecting portion 3 shown square in form, which portion is adapted to engage a member 4 of a lock, which member may be arranged to actuate a bolt or latch 5 thereof. Any suitable means may be employed for establishing such a connection. In the form shown, the member 4 is cylindrical in form, and a pinion 6 is mounted thereon and arranged to engage a toothed rack portion 7 of the bolt 5, so that when the bolt actuating member 4 is turned by the key, the bolt 5 may be moved. Ward members 8 adjustable longitudinally of the key body are arranged about the same so as

to substantially embrace or inclose the key body, the construction being such as will permit relative rotary movement between the wards and the key body, when the latter is inserted in the key hole of a lock. In the form shown, the wards when in position upon the key body, are arranged in cylindrical form, and in order that the wards 8 may be longitudinally adjustable of the core 2, and have a relative rotary movement with respect to said core, the core 2 is provided with a plurality of spaced grooves 9 which extend circumferentially around the said core, and the wards are provided with projecting lips 10 adapted to fit within the grooves 9. The wards 8 may be adjusted to any position longitudinally of the key body by moving each ward so that its projecting lip 10 will engage the proper groove. Further, the grooves being continuous, relative rotary movement may be effected between the wards 8 and the core 2. In the form shown, the wards are provided with tapered sides 11 and 12, the top and bottom 13 and 14 respectively thereof forming cylindrical arcs, so that the said wards may be arranged about the core 2, but it is understood that the wards may be of any suitable form, the essential feature being that the said wards are adjustable longitudinally, and may receive rotary movement relative to the key body. In order that the wards may be maintained in proper relative adjusted position, a tubular casing 15 is provided to fit over the wards, and is provided with an inwardly extending lip or web portion 16 which fits between adjacent wards, and prevents relative rotation between the casing 15 and the said wards, thus holding the said wards in proper relative position. As a means of holding the tubular casing 15 in proper adjusted position, relative to the key body, and to permit relative rotary movement therebetween, an annular collar 17 is arranged upon the core 2, and abuts against a shoulder 18, and is connected with the casing 15 by a screw 19 or other suitable means. Preferably, the core is provided with another groove 20 extending circumferentially therearound, so that the inner end 19' of the screw 19 may extend therein, thus permitting the casing 15 to receive a rotary movement with the wards relative to the core, and to prevent relative longitudinal movement of the casing with respect to the core after the wards have been properly adjusted.

In operation, to change the setting of the ward members, the screws 19 are removed, to permit the removal of the casing 15 after which the adjustment or the setting of the wards is made, and then the casing is re-applied and secured in its proper position by the screws 19.

65 In Fig. 1, a key is shown positioned in a

key hole, showing the manner in which the wards 8 move tumbler members 21 a distance corresponding to the setting of the key. Each of the tumblers 21 is provided with a plurality of pins 22 adjustable thereon and so arranged that when the tumbler is moved a distance corresponding to the setting of the wards, an open pathway will be afforded which will permit a toothed segment 23 arranged circumferentially upon the bolt actuating member 4, to turn which will permit the bolt 5 to be actuated. The tumblers 21 are arranged about the member 4, so as to permit relative rotary movement between the said tumblers and the member 4, when the said member is turned by the key. A tubular casing 24 embraces the tumbler members 21, and holds them in proper relative position, the said casing being provided with an inwardly extending web portion which projects between adjacent tumblers to prevent relative rotation between the said casing and the tumblers.

Preferably, the forward edge of the casing 15 of the key, is provided with a projecting portion 25 which engages a corresponding recess 26 of escutcheon 27 forming the entrance to the key hole. This serves as an indicating mark to facilitate the proper positioning of the key in the key hole, so that it is assured that the wards of the key having a certain setting, will engage the tumblers of the lock adjusted to correspond thereto. By the use of such an indicating means, the key may be properly inserted in the key hole, in the dark.

Each tumbler is pressed forward by a spring finger 28 having one end thereof suitably connected to a plate 29 and the other end of said spring engaging the end 105 of the tumbler 21. In the form shown, the fingers 28 are formed by a stamping from a disk 30 of suitable spring metal. The tubular casing 24 for the tumbler members, may be secured in any suitable manner to the plate 29, and preferably extends forward to the escutcheon plate 27, which may be secured by screws 31 or other suitable means to the door body 32 represented by the broken dotted line. A suitable housing 33 115 may be provided to guide the bolt 5.

While one practical embodiment of the invention has been shown and described herein, it is to be understood that the present invention is not to be limited to the details of construction shown therein, but that various changes and modifications may be made thereof without departing from the spirit and scope of the invention, as particularly pointed out in the appended claims. 120 125

I claim:

1. A combination key comprising a key body including a cylindrical core, ward members arranged about the said core, means to permit longitudinal adjustment of the 130

wards relative to the core, and a means arranged to permit relative rotary movement between the core and the ward members.

2. A combination key comprising a cylindrical core, a handle fixed thereto, ward members longitudinally adjustable relative to each other arranged about the core, and means for holding the wards in proper adjusted position, the said wards and core being constructed to permit relative rotary movement therebetween when the key is inserted in the key hole.

3. A combination key comprising a cylindrical core, a handle fixed thereto, ward members longitudinally adjustable relative to each other arranged about the core, means for holding the wards in proper adjusted position, the said wards and core being constructed to permit relative rotary movement therebetween when the key is inserted in the key hole, and a means fixed to the core for engaging a bolt actuating member of a lock.

4. A combination key comprising a key body, wards arranged about said body and adjustable longitudinally thereof, means arranged to permit relative rotary movement of the wards and the key body, and a means carried by the key body for engaging a bolt actuating member of the lock.

5. A combination key comprising a key body, ward members adjustable longitudinally thereof and arranged to substantially inclose the key body, means for holding the wards in proper adjusted position, and means permitting relative rotary movement between the key body and said wards.

6. A combination key comprising a key body, ward members adjustable longitudinally thereof and arranged to substantially inclose the key body, means for holding the wards in proper adjusted position, means permitting relative rotary movement between the key body and said wards, a means fixed to the key body for engaging a bolt actuating member of the lock, and a means arranged on the key to serve as an indicating mark in properly positioning the key in the key hole.

7. A combination key comprising a key body having a cylindrical core and a handle fixed thereto, the said core having a projection at one end adapted to engage a bolt actuating element of a lock and a plurality of spaced grooves upon the surface thereof, a plurality of ward members adapted to embrace the core, each ward member having a projecting portion adapted to fit the grooved portion, whereby the ward members are adjusted longitudinally of the core, a sleeve adapted to embrace the ward members to hold the same in proper position relative to the ward members, but to permit rotary movement relative to the core.

8. A combination key comprising a cylind-

rical core having a plurality of spaced grooves extending therearound, ward members adapted to be arranged about the core, each of said ward members having a projecting lip adapted to fit within the grooved portion, whereby the wards may be independently adjusted longitudinally of the core and simultaneously to receive a rotary movement relative to the core, means embracing the ward members to hold the same in relatively fixed adjusted position, a collar, another groove extending around the core, and means connecting the last named means with the collar and having a portion extending within said last named groove.

9. A combination key comprising a cylindrical key body having a handle fixed thereto, a shoulder between said core and said handle, a means arranged at one end of the core for engaging a bolt actuating member of a lock, the said core having spaced grooves extending circumferentially about said core, ward members arranged about the cylindrical core, each of said ward members having a projecting lip portion adapted to enter said grooves whereby the said wards may be adjusted longitudinally of the core, a tubular member embracing the wards, an inwardly extending lip carried by said tubular member and arranged to engage one of the ward members to prevent relative rotary movement between said sleeve and said wards, and means to prevent longitudinal movement of said sleeve relative to the core, said means including a collar, and means connecting the collar and the tube, another circumferentially extending groove, the said last named means having a portion projecting within the said last named groove to permit rotary movement of the sleeve relative to the core.

10. A combination key comprising a key body, ward members of uniform construction embracing the said body and adjustable longitudinally thereof, and a means embracing said wards to hold the same in proper relative position, and to permit relative rotary movement between the wards and the key body.

11. A combination key comprising a key body, ward members adjustable longitudinally thereof, means arranged to permit rotary movement between the key body and the wards, and means arranged on the key body to engage a bolt actuating member of a lock.

12. A combination key comprising a cylindrical core having a handle, a casing rotatably mounted thereon, and ward members carried by the said casing.

13. A combination key comprising a cylindrical body, a casing rotatably mounted thereon, ward members arranged in said casing, and means for adjusting said ward members longitudinally of said casing.

14. A combination key comprising a core, means arranged thereon adapted to engage a bolt control member of a lock, a handle therefor, a casing rotatably mounted on said core, ward members arranged in said casing, and means for adjusting said ward members longitudinally thereof.
15. A combination key comprising a cylindrical core having a handle, a casing rotatably mounted thereon, and ward members carried by the said casing, said ward members being held from rotation with respect to the casing.
16. A combination key comprising a key body, ward members adjustable longitudinally thereof, and means arranged to permit relative rotation between the ward members and the key body when inserted in the key hole.
17. A combination key comprising a key body, including a cylindrical core, ward members rotatably arranged about said core, and means to permit longitudinal adjustment of the wards relative to the core.
18. A combination key comprising a cylindrical core, ward members longitudinally adjustable embracing said cylindrical core and rotatable with respect thereto, means for holding said ward members in proper adjusted position and means carried by the core for actuating a bolt control member of a lock, and indicating means arranged on the key to facilitate the proper positioning of the key within the key hole so that the wards of the key will engage tumbler members of the lock having corresponding settings to the said ward members.
